United States Patent Office

Des. 181,492
Patented Nov. 19, 1957

181,492

HEARING AID

Joseph W. Planck and Paul B. H. Smith, Peoria, Ill., as
signors to Tonemaster Manufacturing Company, Peoria,
Ill., a corporation of Illinois

Application November 14, 1956, Serial No. 43,769

Term of patent 14 years

(Cl. D26—14)

Fig. 1.

Fig. 2.

Fig. 3.

Fig. 4.

Fig. 5.

Fig. 1 is a top plan view of a hearing aid, showing our new design;

Fig. 2 is a side elevational view, the opposite side having substantially the same appearance.

Fig. 3 is an end elevational view;

Fig. 4 is a bottom plan view; and

Fig. 5 is an opposite end elevational view.

We claim:

The ornamental design for a hearing aid, as shown and described.
